UNITED STATES PATENT OFFICE.

EDWARD BARRS, OF LONDON, ENGLAND.

LOW-TEMPERATURE DISTILLATION.

Application filed December 19, 1921. Serial No. 523,457.

To all whom it may concern:

Be it known that I, EDWARD BARRS, a subject of the King of England, residing in London, England, have invented certain new and useful Improvements in Low-Temperature Distillation, of which the following is a specification.

This invention is for improvements in or relating to low temperature distillation and 10 has for its object to provide a cheaper and more efficient form of distillation retort than has heretofore been in use.

It has previously been proposed to provide these distillation retorts with a fireclay 15 bottom beneath or in which the heating-conduits or flues were disposed. Such a bottom, however, adds to the expense of manufacture and up-keep, and hinders the transmission of heat which is thus lost to 20 the material under treatment.

A retort for low temperature distillation of coal, according to the present invention, is characterized by the working-bottom being composed of coal and having formed or 25 embedded in it the flues whereby the retort is heated.

The heating-conduits or flues may be laid on the upper surface of the retort-bottom (which is below the working-bottom) in 30 such manner that the material will surround and lie on the flues, that portion of it which lies above the flues being alone intended to be moved forward through the retort, for the purpose of leaving a layer to 35 serve as the working-bottom of the retort.

There may be combined with the flues means (for example a reciprocating rabble) for moving the material through the retort and guides therefor so arranged as to prevent the said means from entering the area 40 occupied by the flues.

The accompanying drawing shows a longitudinal vertical section through a retort, the upper and middle portions of which are 45 broken away as being unnecessary to the understanding of the invention.

The retort-chamber A is provided with a bottom B which may be of fire-clay as before, but the expense of upkeep is reduced 50 because it is not subjected to the hard usage resulting from the continual movement of the material on the bottom of the retort, as is the case when this bottom contains the heating-flues. The heating flues C take the 55 form of self-contained conduits conveniently

of metal and are supported on rollers C¹ on the upper surface of the retort-bottom B. At the rear end of the retort a stuffing-box C² is provided for each conduit, and the conduits extend through these stuffing-boxes 60 and thus through the back wall of the chamber to a collecting chamber A¹ whence the medium for heating the retort escapes from the conduits. The forward ends of the conduits are provided each with a downwardly-directed extension D which is connected to the conduit by a right-angled elbow or joint D¹ and these extensions D are connected in pairs, two to a right-angled elbow or joint D² which carries an extension 70 shown in chain-line at D³, and another two to a right-angled elbow or joint D⁴ which receives in it a further extension D⁵. It will be observed that the conduits C with their extensions D constitute right-angled 75 members lying in vertical planes and that the extensions D³ and D⁵ lie with their through axes at right-angles to the planes occupied by the conduits with their first-mentioned extensions, so that provided the 80 joints are loose a rocking-action can take place about the extensions D³ and D⁵ as the main conduits C expand and contract.

The material enters the retort-chamber by way of the hopper E and it is fed forward 85 by a reciprocating rabble F which is constructed and operates as is described in my earlier United States patent specification No. 523,456 filed December 19, 1921, "Rabbles for low temperature coal-distillation purposes or other purposes where a like movement of the material is required". This rabble has depending grids or scrapers F¹ and reciprocates in the manner described in the said earlier specification along two 90 tracks, an upper and a lower, part of the lower track being shown at G and part of the upper at G¹. These two tracks are connected to ramps, whereof one is shown at G², by which the rollers F¹ of the rabble 95 rise towards the end of its forward travel. A shunt plate H has lugs H¹ for bridging the gaps in the upper track at the top of the ramps. When the rabble moves backwards its rollers first travel over these bridge pieces H and before dropping through the gaps in the upper track, abut against stops, such as H², on the shunt plate 100 and shift the latter so far that the ramps are left free for the next ascent of the rabble. 105

The lower ends of the grids or pushers F² of the rabble travel forward in the plane indicated by the chain-line G and the return movement is at a higher level. It thus follows that the material fed in through the hopper E is spread along the floor of the chamber between and over the conduits C and only that part which lies above the line G is moved forward through the chamber. The material under treatment, therefore, provides its own working-bottom and the bottom B is not subjected to the abrasion and other hard usage which it is ordinarily subjected to when the whole of the material is moved along it and the flues are embedded in it. The working-bottom provided by the material under treatment allows a greater percentage of heat to reach the material fed through the retort than is possible when the flues are mounted within a fire-clay bottom.

It will thus be seen that by means of this invention a cheaper retort is provided, as the bottom is less expensive to construct than one in which flues have to be formed or embedded, the cost of upkeep is less and the heat generated is more efficiently used than is the case with retorts at present employed.

It will be appreciated that the flues need not always be self-contained, for example if metal flues are used in the first instance and the gases which traverse them are such as to attack the metal this would in time become destroyed by corrosion and the flues will merely take the form of cored ways through the working-bottom, and, indeed, in some cases where it is known that corrosive gases are going to be employed as the heating-medium, the working-bottom may be made up of partially distilled coal tamped into position around cores which may afterwards be withdrawn. Such a working-bottom may be made up in the retort or it may be introduced into the retort after it has been made.

What I claim as my invention and desire to secure by Letters Patent is:—

1. For use in the low-temperature distillation of fuel, a retort having a bottom of refractory material, means comprising at least one depending scraper movably mounted in the retort for moving fuel forward therethrough, the bottom of which scraper is located above the refractory bottom and is arranged to move along a path spaced away from the refractory bottom, and heating flues located in the space between the refractory bottom of the retort and the said path along which the bottom of said scraper travels.

2. For use in the low-temperature distillation of fuel, a retort having a bottom of refractory material, means comprising at least one depending scraper movably mount-

ed in the retort for moving fuel forward through the retort along at the working level located above the refractory bottom of the retort, guides for said means so arranged that the bottom of the scraper moves along at the level of the said working bottom, rollers arranged in rows on the refractory bottom of the retort, and heating flues carried each by a row of said rollers and located in the space between the said working bottom and the refractory bottom.

3. For use in the low-temperature distillation of fuel, a retort having a bottom of refractory material, means comprising at least one depending scraper movably mounted in the retort for moving fuel forward through the retort along a working level located above the refractory bottom of the retort, self-contained heating conduits located in the space between the said bottoms and extending through a wall of said retort, and stuffing boxes, one for each conduit in said wall.

4. For use in the low-temperature distillation of fuel, a retort having a bottom of refractory material, means comprising at least one depending scraper movably mounted in the retort for moving fuel forward through the retort along a working level located above the refractory bottom of the retort, guides for said means so arranged that the bottom of the scraper moves along a path at the level of the said working bottom, self-contained conduits for a heating medium located in the space between the said bottoms and extending at one end through a wall of said retort and having each an elbow at its other end, stuffing boxes, one for each conduit in said wall, main conduits for a heating medium disposed at right-angles to said self-contained conduits and having vertical T-pieces each connected to one of said elbows, the joints of the T-pieces with the main conduits being fluid-tight but sufficiently loose to permit of their connections with the elbows to rock about the main conduits when the said self-contained conduits expand and contract.

5. For use in the low-temperature distillation of fuel, a retort having a bottom of refractory material adapted to support a layer of combustible material providing a working bottom at the working level for carrying the fuel undergoing distillation, and flues for a heating medium in said layer below the working level for heating the said layer and fuel.

6. For use in the low-temperature distillation of fuel, a retort having a bottom of refractory material adapted to carry a layer of coked material providing a working bottom at the working level for carrying the fuel undergoing distillation, flues for a heating medium in said layer below the working level for heating the said layer and fuel, and

means mounted in the retort for moving fuel forward through the retort along the said working bottom.

7. For use in the low-temperature distillation of fuel, a retort having a bottom of refractory material adapted to carry a layer of combustible material providing a working bottom at the working level for carrying fuel undergoing distillation, self-contained flues for a heating medium embedded in said layer below the working level and extending through a wall of said retort, and stuffing boxes, one for each flue, in said wall.

8. For use in low-temperature distillation of fuel, a retort having a bottom of refractory material adapted to carry a layer of coked material providing a working bottom at the working level for carrying fuel undergoing distillation, rollers arranged in rows on the refractory bottom, and self-contained conduits for a heating medium embedded in said layer below the working level and carried each by a row of said rollers, which conduits extend fluid tight through a wall of the retort.

9. For use in the low-temperature distillation of fuel, a retort having a bottom of refractory material adapted to carry a layer of combustible material providing a working bottom at the working level for carrying fuel undergoing distillation, self-contained conduits for a heating medium embedded in said layer below the working level and extending at one end through a wall of said retort and having each an elbow at its other end, stuffing boxes, one for each conduit, in said wall, main conduits for a heating medium disposed at right angles to said self-contained conduits and having T-pieces, each connected to one of said elbows, the joints of the T-pieces with the main conduits being sufficiently loose to permit of their connec-

tions with the elbows to rock about the main conduits when the said self-contained conduits expand and contract.

45

10. For use in the low-temperature distillation of fuel, a retort having a bottom of refractory material adapted to carry a layer of coked material providing a working bottom at the working level for carrying fuel undergoing distillation, flues for a heating medium embedded in said layer below the working level, means mounted in the retort for moving fuel through the retort along the said working bottom, and guides for said means so arranged as to prevent the latter from entering the layer below the said working bottom.

50

11. For use in the low-temperature distillation of fuel, a retort having a bottom of refractory material adapted to carry a layer of coked material providing a working bottom at the working level for carrying fuel undergoing distillation, rollers arranged in rows on the refractory bottom, self-contained conduits for a heating medium embedded in said layer below the working level and extending at one end through a wall of said retort, which conduits are carried each by one of said rows of rollers, and have each an elbow at its other end, stuffing boxes, one for each conduit, in said wall, and main conduits for a heating medium disposed at right angles to said self-contained conduits and having vertical T-pieces and each connected to one of said elbows, the joints of the T-pieces with the main conduits being sufficiently loose to permit of their connections with the elbows to rock about the main conduits when the self-contained conduits expand and contract.
